UNITED STATES PATENT OFFICE.

ELMER R. THOMAS AND PEARLEY E. LANGFITT, OF SHIDLER, OKLAHOMA.

PUMP JACK.

Application filed November 17, 1925. Serial No. 69,661.

Our present invention pertains to pump jacks, and is designed more particularly as a practical improvement upon the pump jack constituting the subject of our Letters-Patent No. 1,553,486, and dated September 15, 1925.

The general object of our said invention is the provision of a pump jack of simple, inexpensive and strong construction and one susceptible of ready adjustment for the purpose of preventing breakage in the event of a mishap, and also susceptible of convenient adjustment in order to assure the same operating under all conditions to the best advantage.

Other objects and practical advantages of the invention will be fully understood from the following description and claims when the same are read in connection with the drawings, accompanying and forming part of this specification, in which:—

Figure 1 is a side elevation of the best exemplification of our present invention of which we are aware.

Figure 2 is a vertical transverse section taken in the plane indicated by the line 2—2 of Figure 1.

Figure 3 is a horizontal section taken in the plane indicated by the line 3—3 of Figure 1.

Figure 4 is a fragmentary end elevation illustrating the means employed for effecting connection between the polish rod and the walking beam.

Similar numerals of reference designate corresponding parts in all of the views of the drawings.

The walking beam of our improved jack is designated by 1, and is fulcrumed at 2 between two spaced uprights 3 which are fixed to sills 4 on a base 5, and are braced by bars 6. The walking beam 1 is formed by two spaced bars 6 and between the central portions of the bars 6 is fixed a body member 7, integral with which is a pendent portion 8 which receives the fulcrum pintle and which rests under the lower edges of the bars 6 so as to strongly support the said bars on the fulcrum pintle. The upper portion of the body 7 is flanged at 8 to bear on the upper edges of the bars 6, and rising from the flanges 8 and integral therewith are webs 9 disposed at right angles to each other, the said webs 9 being provided with a seat 10 in the upper ends thereof for a

truss rod 11, which is connected at one end to the head 12 between end portions of the bars 6 as designated by 13. The portion of the truss rod 11 at the opposite side of the body portion 9, with reference to the connection 13 is threaded as designated by 14 for the engagement of a turn buckle 15 which is appropriately threaded to engage the thread of another rod section 16, the rod 16 extending to a block 17 between end portions of the bars 6 and being threaded for the engagement of a nut 18 at the outer end of the said block. Manifestly when constructed in the manner described, the walking beam will be capable of withstanding great shocks and strains, and whenever occasion demands the walking beam may be adjusted to compensate for sagging of either end thereof by simply turning the turn buckle 15.

The head 12 is interposed between end portions of the walking beam bars 6 and is provided with flanges 20 above and below the bars 6, whereby practically all strain is taken off the transverse connecting bolts 21. The upper outer portion of the head 12 is in the form of an apertured lug 22, and to said lug 22 is pivotally connected at 23 the bifurcated upper end of a pendent and swingable member 24, the said member 24 being adapted to normally rest against the flat face 25 of the head 12. The member 24 is characterized by a lower bifurcated hook portion, said portion being numbered 26, and its bifurcation being adapted to accommodate or receive a polish rod 27. The said polish rod 27 is provided with lateral projections 28 fixed thereto, and the said lateral projections 28 are adapted to seat in the hook 26 at opposite sides of the bifurcation thereof, whereby a strong connection may be effected between the polish rod 27 and the member 24. The said lateral projections of the polish rod 27 are of circular form in cross section, and the inner side of the bill of the hook 26 is correspondingly rounded so as to permit free movement of the hook 26 about the said lateral projections 28. Manifestly this provision averts binding during the vertical oscillation of the walking beam 1, the member 24 being adapted incident to up and down movements of the walking beam to swing relative to the face of the head 12 so that at no time will any lateral pull or strain be imposed on the

polish rod, and in consequence the jack will operate evenly and easily at all times under normal conditions.

Fixed to the sills 4 at a point remote from 5 the polish rod 27 is a standard 30, and pivoted to said standard 30 is a link 31, adjustably connected by rod sections 32 and a turn buckle 33 with a clip 34 about a casting 35 or other appropriate anchoring means.

10 By virtue of the connection described it will be manifest that the link 31 may be adjusted and may be adjustably fixed in the most advantageous position for the working of what we denominate the truss frame 36 15 of our improvement, the said truss frame being designed at 37 to be connected with a shackle rod line.

In accordance with another part of our present invention, the shackle member 40 20 which bears on and is interposed between and connected to end portions of the bars 6, serves to receive a pintle 41 by which are connected pitmen 42 which are pivotally connected at 43 to a shackle member 44 25 which bears against the lower edges of the lowermost bars 45 of the truck frame, and is fixedly connected in appropriate manner to said bars 45. Constructed in the manner specifically described, the connection between 30 the truck frame 36 and the walking beam 1 is extremely simple and at the same time strong and well adapted to withstand all of the shocks and strains imposed upon it.

The shackle 37 is engaged with a saddle 50 35 on the upright portion of the truck frame 36, and at its upper end the said upright portion is provided with an eye 51.

A brace 52 is interposed between and fixed to the sills 4 and the uprights 3, and connected at 53 to the said brace is a chain 54. 40 Pivoted at 55 to a short standard 56 carried by the sills 4 is a longitudinally and vertically swingable member 57 on which is an eye 58 for cooperation with the bill of a hook 59, flexibly connected at 60 to the before mentioned brace 52. Manifestly by engaging the hook 59 with the eye 58, the member 57 may be strongly though detachably maintained in a substantially upright 45 position so as to prevent undue downward movement of the adjacent arm of the walking beam in the event of any breakage or other mishap occurrence such as would tend to bring about undue downward movement 50 of the said arm.

It will also be apparent that in the event of breakage or mishap or for any other reason, the arm of the walking beam adjacent to the truck frame 36 may be tied or anchored, the said tying or anchoring being 60 calculated to prevent upward movement of the said arm of the walking beam, and being effected by placing the chain 54 or rather one of the links thereof over the eye 51 on the truck frame, and then, if necessary, plac-

ing a cotter pin through the eye 51 above the said links. After either of the manipulations indicated, the hook 59 may be readily disengaged from the eye 58 to permit of the restoration of the hook and the member 57 to the idle positions shown in Figure 1, and likewise the chain 54 may be expeditiously and easily disconnected from the eye 51, whereupon the said chain may be permitted to hang in the idle position shown in Figure 1.

The means hereinbefore described in detail whereby a straight lift is afforded and assured for the polish rod constitutes a highly important feature of our invention. 80

We have specifically described the construction and relative arrangement of all of the elements embraced in the present and preferred embodiment of our invention in order to impart an exact understanding of 85 the said embodiment in all of its details. We do not desire, however, to be understood as confining ourselves to the specified construction and arrangement of parts, our invention being defined by our appended 90 claims within the scope of which structural changes and changes in arrangement may be made without departure from our invention. 95

Having described our invention, what we claim and desire to secure by Letters- 95 Patent, is:—

1. In a pump jack, the combination of spaced supporting means, a walking beam having spaced bars above said supporting means, a body fixed between the bars of the walking beam and having portions above and below said bars and against the same and also having a pendent portion disposed between and pivotally connected to the supports, and further having an upstanding portion above the spaced bars, and a truss extending over said upstanding portion and connected with the end portions of the bars. 100

2. In a pump jack, the combination of spaced supporting means, a walking beam 105 having spaced bars above said supporting means, a body fixed between the bars of the walking beam and having portions above and below said bars and against the same and also having a pendent portion disposed between and pivotally connected to the supports, and further having an upstanding portion above the spaced bars, and a truss extending over said upstanding portion and connected with the end portion of the bars; 110 the said upstanding portion above the bars of the walking beam being formed by longitudinally and transversely disposed webs. 115

3. In a pump jack, the combination of a 120 walking beam, a truss frame, members carried by the walking beam and the truss frame, the member of the walking beam being at the remote side thereof from the truss frame and the member of the truss frame being at the remote side thereof from 125 130

the walking beam, and pitmen disposed at opposite sides of the walking beam and truss frame and also at opposite sides of said members and pivotally connected with said members.

4. In a pump jack, a walking beam, a support therefor, a truss frame, swingable means adapted when positioned in substantially upright position below the walking beam to prevent downward movement of one

arm thereof, adjustable means on the support for maintaining said member in said substantially upright position, and adjustable means on the support adapted to be detachably connected with the truss frame to 15 anchor the same to the support.

In testimony whereof we affix our signatures.

ELMER R. THOMAS.

PEARLEY E. LANGFITT.
